LOCK

Filed April 11, 1929

INVENTOR
Morris Sheinman
BY
Marie Block
ATTORNEY

UNITED STATES PATENT OFFICE

MORRIS SHEINMAN, OF NEW YORK, N. Y.

LOCK

Application filed April 11, 1929. Serial No. 354,273.

This invention relates to improvements in locks and has for one of its objects the provision of a lock that can be used by itself in lieu of a padlock or in combination with the bolt portion of a cylinder lock and operated by a single key to lock a door on both the inside and outside and act as anti-jimmy agent when so used.

Another object of the invention is to provide a lock having a bar which extends across the meeting point of the door and frame, which bar is freely mounted at one end thereof on an eye bolt or staple secured to the door frame, and provided with a threaded hole or opening at its opposite end, adapted to engage a threaded portion on the cylinder of the lock and draw the said bar against the door when operated by a key in locking direction and to disengage the bar from the cylinder when operated in opening direction.

A further object of the invention is to provide a lock of this character adapted to be connected to any make of cylinder lock to lock a door from both sides thereof by the same key and to act as an anti-jimmy agent to prevent the jimmying of the inner lock.

A still further object of the invention is to provide an auxiliary outer lock of this nature that can be readily connected to an inner lock which inner lock may be operated from the inside independently from the said auxiliary lock.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests

a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which

Figure 1 is a fragmentary view of the outside of a door, showing my improved lock in locked position and used independently of any other lock.

Figure 2 is a sectional view taken on line 2—2 Fig 1.

Figure 3 is a view looking from the inside of the door or from the right of Fig. 2.

Figure 4 is a top plan view partly in section of my improved lock used in combination with an inner lock.

Figure 5 is a detail view of the cylinder portion of my lock.

Figure 6 is a perspective view of the cylinder retaining disk, and inner lock roll back or lever.

Figure 7 is a sectional view of the cylinder housing.

Figure 8 is a side view in elevation of the connecting bar which connects the inner and outer locks.

Referring now to the drawings in detail 10 indicates a portion of a door and 11 a portion of the door frame to which there is secured a plate 12 provided with an eye-bolt 85 or staple 13 from which bolt may be suspended a bar 14 by means of a slot 15 at one end of the said bar. The said bar 14 is provided at the end opposite to the slot 15 with a threaded hole or opening 16 adapted to 90 engage a threaded portion 17 of a cylinder 18 rotatably mounted in a pin housing 20 which fits into a suitable bore 21 in the door. Threads of various pitches may be used depending upon the nature and size of the lock. 95

The housing 20 is provided with two sets of holes or openings 22 and 23 provided with pins or tumblers 24 and 25, and springs 26 and 27 pressing the said pins against the cylinder 18 and when the cylinder is in posi- 100

tion as shown in Figure 2 the said pins 24 are pressed into openings 30 and against tumblers or pins 31 in the said openings which pins are operated by a serrated key for locking or unlocking.

The housing 20 is maintained in the bore 21 by means of screws 33 threaded into the end of the said housing and which pass through openings in a plate 34 which abuts 10 the inner surface of the door. The cylinder 18 is maintained in the housing 20 by means of a disk or plate 35 abutting the end 36 of the housing and secured to the said cylinder by screws 37. Plates 38 and 39 slidably 15 maintained in the housing 20 prevent the loss or displacement of the pins 24 and 25 and their respective springs 26 and 27 as well as the pins 31.

In Fig. 4 I have shown my lock in combination with a lock 44 so that the door may be locked on both sides thereof. In this form I employ a connecting bar 45 which fits into a slot 46 and passes through a slot 47 in the disk 35 and extends into a slot 49 in a lever 25 48 in the lock 44, which lever is adapted to engage and operate the locking bolt mechanism 50 for locking and unlocking the said lock 44. This lock 44 may be operated from the inside independently of the outer lock 30 by means of a finger piece 51 in operative engagement with a bolt 52, and from the outside by means of a key inserted into the key slot 53 located in the cylinder 18. It will be seen that due to the fact that I employ a 35 plurality of sets of tumblers, I am enabled to revolve the cylinder and withdraw my key in one half turns, because when the cylinder 18 is revolved one half turn either of the sets of tumblers 24 or 25 will be in communication with the pins 31 and in line with the openings 22 or 23 in the housing 20 in which position the key can be inserted and withdrawn as the tumblers will be free to be pushed upwardly by the said key against the 40 springs 26 or 27 in the housing.

It will also be seen that I may employ various pitch threads on the cylinder 18 and bar 14, and still be enabled to withdraw the key in fractions of one half turns, the only difference being that when employing a coarse thread I will have to make fewer of such fractional turns than when a finer thread is employed.

The object of providing two sets of tumblers is to enable the bar 14 to be brought as close as possible to the flange on the housing 20. For trunks, comparatively small locks have to be used, and in such cases a comparatively fine thread has to be used, consequently it may be necessary to revolve the cylinder one and a half revolutions to bring the bar 14 close to the housing 20.

The slot 15 provides means to take up any 35 expansion or contraction of the door and also

permits the use of different lengths of locks 44 on the inside of the door.

The operation of the lock is as follows:

A key which will properly align the tumblers, is inserted into the key slot 53, the bar 14 is placed with its opening 16 against the portion 17 of the cylinder and the key is revolved in locking direction, this revolution of the cylinder will cause the bar 14 to be threaded on to the cylinder and simultaneously lock the lock 44. By revolving the cylinder in the opposite direction the bar will become unthreaded or disengaged from the cylinder. When the lock 44 is operated from the inside the outer lock will not be 80 effected.

From the foregoing it will be seen that I have provided a simple and efficient lock adapted to be used separately or in combination with another lock to lock a door from 85 one or both sides thereof.

Having described my invention what I claim as new and desire to secure by Letters Patent is

1. A door lock comprising a housing, a key operated cylinder rotatably mounted in the housing, sets of locking tumblers in operative engagement with the housing and cylinder, a threaded portion on the cylinder extending beyond the housing, and a bar 90 adapted to be suspended from the door frame and having a threaded opening to engage the threaded portion on the cylinder for the purpose specified.

2. A door lock, comprising a housing, a 100 rotatable cylinder in the housing, key operated cylinder locking means extending from the housing into the cylinder, a threaded portion on the cylinder extending beyond the housing, and a bar adapted to be suspended from the door frame and having a threaded opening to engage the threaded portion on the cylinder for the purpose specified.

3. A door lock, comprising a housing, a rotatable cylinder in the housing, a set of 110 key operated tumblers in the cylinder, a complementary set of spring pressed tumblers in the housing extending into the cylinder and in engagement with the first mentioned tumblers, a threaded portion on the cylinder extending beyond the housing, and a bar adapted to be suspended from the door frame and having a threaded opening to engage the threaded portion on the cylinder for the purpose specified.

4. A door lock, comprising a housing, a rotatable cylinder in the housing, a set of key operated tumblers in the cylinder, a complementary set of spring pressed tumblers in the housing extending into the cylinder and in engagement with the first mentioned tumblers, a second set of spring pressed tumblers in the housing located diametrically opposite to the first mentioned set of spring pressed tumblers, a threaded portion on the 125 130

cylinder extending beyond the housing, and a bar adapted to be suspended from the door frame and having a threaded opening to engage the threaded portion on the cylinder for the purpose specified.

5 5. In combination with a door lock, an auxiliary key operated cylinder lock, a threaded portion on the cylinder lock, a bar adapted to be suspended from the door frame and provided with a threaded opening to engage the threaded portion of the cylinder lock for the purpose specified and a connector between the said locks.

10 6. A key operated door lock comprising a housing, a cylinder in the housing, a threaded portion on the cylinder, a bar adapted to be suspended from the door frame and having a threaded opening to engage the threaded portion on the cylinder, and means associated with the housing and cylinder whereby the cylinder may be rotated in one half revolutions to withdraw the key.

15 7. A key operated door lock comprising a housing, a cylinder in the housing, a threaded portion on the cylinder, a bar adapted to be suspended from the door frame and having a threaded opening to engage the threaded portion on the cylinder, and means associated with the housing and cylinder whereby the cylinder may be rotated a fractional portion of a revolution to locking and unlocking position.

20 8. In combination with a lock, a housing, a key operated cylinder in the housing, a connector connecting the cylinder and lock, a threaded portion on the cylinder and a bar adapted to engage the said threaded portion of the cylinder for the purpose specified.

25 In testimony whereof I hereunto affix my
signature.
